UNITED STATES PATENT OFFICE.

NICHOLAS MEDVED, OF CANTON, OHIO.

ADJUSTABLE RADIOCOILS.

Application filed November 20, 1926. Serial No. 149,736.

The invention relates to coils for use in electrical circuits, and more particularly in radio circuits, in various arrangements such as for radio frequency transformers, and includes improvements in the radio coils set forth in my prior application for patent filed April 6, 1926, Serial No. 100,093; and the objects of the improvements are to provide a more convenient and economical construction and arrangement for the coils of my aforesaid prior application, and to provide, as for use in circuits including a plurality of radio frequency vacuum tubes, a plurality of sets of my improved radio coils arranged for use as for radio frequency transformers in connection with said tubes, there being independent means associated with each set of adjustable coils whereby the several sets may be independently adjusted and the several circuits may be thereby adjusted or balanced with each other, and means for simultaneously adjusting as for tuning purposes the plurality of balanced transformers.

A further object of the invention is to provide a modified form of my improved radio coils set forth in my aforesaid prior application.

The foregoing and ancillary objects are attained in the present invention by constructions and arrangements hereinafter described in detail, and illustrated in the accompanying drawings forming part hereof, in which—

Figure 1 is a side elevation with portions in axial vertical cross section of a single set of my improved adjustable radio coils, as arranged for use as an adjustable radio frequency transformer;

Fig. 2, a side elevation with portions in axial vertical cross section of a plurality of sets of my improved adjustable radio coils, arranged for adjustments independent of each other, and simultaneous with each other; and

Fig. 3, a top plan view thereof.

Similar numerals refer to similar parts throughout the drawings.

The improved single set of my adjustable radio coils, arranged as for use as a radio frequency transformer, illustrated in Fig. 1, includes a base 1 which may be made of molded dielectric material such as hard rubber, and provided with upwardly extending end bearing brackets 2^a and 2^b, at the upper ends of which are secured the ends of the longitudinally extending parallel upper and lower coil support bearing and slide rods 3 and 3'

which may likewise be made of hard rubber.

The ends of the rods 3 and 3' preferably fit in suitable apertures 4 in the upper ends of the bearing brackets 2^a and 2^b, and the ends of the rods may be secured in their bearing apertures in the brackets as by pins 5.

Between the bearing brackets, the rods 3 and 3' pass through suitable apertures 6^a in the smaller base wall 7^a of one preferably conical frustrum coil support 8^a, and through suitable sliding apertures 6^b in the smaller base wall 7^b of another preferably conical frustrum coil support 8^b.

The coil supports 8^a and 8^b are preferably of identical hollow conical frustrum form, and include the conical walls 9^a and 9^b diverging outwardly from the smaller frustrum base walls 7^a and 7^b, respectively; and the conical walls 9^a and 9^b include outer conical surfaces 10^a and 10^b, and inner conical surfaces 11^a and 11^b, both surfaces being preferably coaxial and having the same taper.

The supports 8^a and 8^b are preferably coaxially mounted on the rods 3 and 3' with their larger frustrum bases adjacent each other as shown, and the smaller base wall 7^a of the support 8^a preferably having its outer face abutting or closely adjacent the inner face of the bracket 2^a, and being secured to the rods 3 and 3' as by the pins 12.

By these means, the support 8^a is fixed in position upon the rods 3 and 3', and the support 8^b is slidable thereon, for varying the longitudinal axial distance between the supports for purposes hereinafter to be explained in detail.

For providing means for very finely adjusting the longitudinal distance between the supports 8^a and 8^b, the base wall 7^b of the support 8^b is provided with a threaded axial aperture 13 in which a rotatable adjusting screw shaft 14 longitudinally fits and extends.

One bearing end 14' of the shaft 14 preferably extends through an unthreaded loose axial opening 15 in the base 7^a of the support 8^a, and the bearing end 14' of the shaft 14 is preferably supported in a bearing socket 16 in the bracket 2^a.

The other bearing end 14'' of the screw shaft 14 may be provided with an outer thrust collar 17 fitting in a suitable bearing aperture 18 in the bracket 2^b, and a washer 19 and locking nuts 20 may be provided upon the shaft for suitably abutting the washer 19 against the inner face of the bracket 2^b.

whereby the shaft 14 is secured against longitudinal movement, but adapted to be rotated as by means of a knob 21 secured as by a set screw 22 upon the outer extremity 5 of the bearing end 14" as illustrated.

The conical walls 9^a and 9^b of the supports 8^a and 8^b, are preferably made of dielectric material such as hard rubber, and are preferably provided with openings 23 10 for reducing the quantity of the dielectric material required for the supports.

The outer surfaces 10^a and 10^b of the supports carry respectively outer spirally wound conical coils 24^a and 24^b, preferably of the 15 character described in my aforesaid application, Serial No. 100,093; while the surface 11^a may support an inner spirally wound conical coil 25^a, of a similar character, and another inner spirally wound conical coil 26^a may 20 be spaced from and carried within the coil 25^a as by means of a dielectric conical spacer 27.

Adjacent terminals 24^{a'}, and 24^{b'} of the coils 24^a and 24^b may be connected with each 25 other as illustrated to form a split secondary for using the adjustable coils herein set forth as an adjustable radio frequency transformer.

The outer terminal 25^{a''} of the coil 25^a and the inner terminal 26^{a''} of the coil 26^a 30 may be connected to each other to form a balancing primary for the split secondary.

The other terminals 24^{a''}, 24^{b''}, 26^{a''} and 25^{a''} are here shown free, ready to be incorporated in the aforesaid circuit.

35 The aforesaid construction and arrangement for my adjustable coils is more economical to manufacture and assemble than the arrangement disclosed in my prior application, Serial No. 100,093.

Moreover the coils of the present disclosure 40 may be coaxially alined with each other with greater accuracy over the whole range of adjustment; and are adapted for a greater range of adjustment than is possible by the 45 use of the disclosure of my prior application. The slide rods 3 and 3' accurately maintain the coaxial arrangement of the coil supports, regardless of the longitudinal distance between them.

50 The present longitudinal adjusting means, including the long screw 14, enables a very great variation in the longitudinal distance between the coaxial coils, whereby when the coils are used in a circuit such as a radio 55 circuit, they may be adjusted to pass a current having a frequency, varying much more slightly from preceding or succeeding unpassed frequencies, than can be accomplished by adjustable coils of different construction.

60 In other words by the use of the present coils, very fine tuning of radio frequency circuits is made possible.

The coils when used in radio circuits have also been found to have a very small mutual 65 inductance; a given coil may be used sub-

stantially over the whole range of radio broadcasting frequencies; and by reason of the very fine frequency adjustments possible, a greater selectivity in the radio receiving circuit is obtained.

In addition to the aforesaid advantages of my improved adjustable coils for radio circuits, the adjustable coils may be advantageously used as will be obvious to persons skilled in the art, in other alternating or oscillating current circuits, such as telephone circuits or the like, wherever very fine frequency adjustments are desired.

As illustrated in Figs. 2 and 3, a plurality of sets of my improved radio coils may be 80 arranged for use as for a plurality of radio frequency transformers in radio circuits which may include a plurality of radio frequency vacuum tubes, it being understood that in such circuits a single adjustable radio 85 frequency transformer is usually associated with each tube, and it is desirable to balance the several tube and transformer circuits with each other; and for tuning purposes it is moreover desirable, after the several tube and transformer circuits have been 90 balanced with each other, to simultaneously vary the transformer adjustments of the same.

The improved sets of adjustable radio coils 95 arranged for use as a plurality of radio frequency transformers, illustrated in Figs. 2 and 3, are adapted for the foregoing purposes, and the arrangement includes a base 101 which may be made of molded dielectric 100 material such as hard rubber, and provided with a plurality of upwardly extending end bearing brackets 102^a and 102^b, and intermediate bearing brackets 102^c and 102^d, at the upper ends of which are secured longitudinally extending parallel upper and lower coil support bearing and slide rods 103 and 103' which may likewise be made of hard rubber. The ends of the rods 103 and 103' preferably 110 fit in suitable apertures 104 in the upper ends of the bearing brackets 102^a and 102^b, and the ends of the rods may be secured in their bearing apertures in the brackets as by pins 105.

Between each of the bearing brackets 102^a and 102^c, 102^c and 102^d, and 102^d and 102^b, the rods 103 and 103' pass through suitable apertures 106^a in the smaller base wall 107^a of one preferably conical frustum coil support 108^a, and through suitable sliding apertures 106^b in the smaller base wall 107^b of another preferably conical frustum coil support 108^b.

The coil supports 108^a and 108^b are preferably of identical hollow conical frustum form, and include the conical walls 109^a and 109^b diverging outwardly from the smaller frustum base walls 107^a and 107^b; and the conical walls 109^a and 109^b include outer conical surfaces 110^a and 110^b, and inner conical 130

surfaces 111^a and 111^b, both surfaces being preferably coaxial and having the same taper.

The sets of supports 108^a and 108^b are preferably coaxially mounted on the rods 103 and 103' with the larger frustum bases of the supports of each set adjacent each other as shown, and the smaller base walls 107^a of the supports 108^a preferably having their outer base surfaces closely adjacent the opposed surfaces of the brackets 102^a, 102^c and 102^d.

Means are provided for independently varying the longitudinal distances of the supports 108^a from each other, which preferably include stub shafts 112^a, 112^c and 112^d journaled respectively in the upper ends of the brackets 102^a, 102^c and 102^d, between the rods 103 and 103', and coaxial with the supports 108^a.

20 The stub shafts are provided with threaded ends 112^{a'}, 112^{c'} and 112^{d'} which screw in suitable apertures in the support base walls 107^a.

At the other ends, the stub shafts are provided with suitable preferably removable knobs 112', which may be secured thereon as by pins 112" as shown.

The knob and threaded ends of the stub shafts are preferably of greater diameter than the central portions journaled in the bearing brackets, whereby the stub shafts are secured against longitudinal thrust, and whereby rotation of the stub shafts by means of the knobs 112' will vary the longitudinal position of each support 108^a with respect to its adjacent bracket, and thereby providing means for independently varying the longitudinal distances of the supports 108^a from each other.

40 For providing means for simultaneously and very finely adjusting the longitudinal distances between the several supports 108^b, and the adjacent supports 108^a, the base walls 107^b of the supports 108^b are each provided with a threaded axial aperture 113, through all of which a single rotatable adjusting screw shaft 114 longitudinally fits and extends. The screw shaft 114 also preferably extends through unthreaded loose axial openings 115 in the stub shafts 112^c and 112^d, and one bearing end 114' of the screw shaft 114, is preferably supported in a bearing socket 116 in the stub shaft 112^a.

The other bearing end 114" of the screw shaft 114 may be provided with an outer thrust collar 117 fitted in a suitable bearing aperture 118 in the bracket 102^b, and a washer 119 and locking nuts 120 may be provided upon the shaft for suitably abutting the washer 19 against the inner face of the bracket 102^b whereby the shaft 114 is secured against longitudinal movement, but adapted to be rotated as by means of a knob 121 suitably secured upon the outer extremity of the bearing end 114" as illustrated.

The conical walls 109^a and 109^b of the supports 108^a and 108^b are preferably made of dielectric material such as hard rubber, and are preferably provided with openings 123 for reducing the quantity of the dielectric material required for the supports.

The outer surfaces 110^a and 110^b of each of the supports carry respectively outer spirally wound conical coils 124^a and 124^b, preferably of the character described in my aforementioned application, Serial No. 100,093; while the surface 111^a of each support may sustain an inner spirally wound conical coil 125^a, of a similar character.

Adjacent terminals 124^{a'} and 124^{b'} of the coils 124^a and 124^b may be connected with each other as illustrated to form a split secondary, for using each set of the adjustable coils as an adjustable radio frequency transformer.

The terminals 125^{a'} and 125^{a''}, of the coils 125^a, and the terminals 124^{b''} and 124^{b'} of the split secondary coils 124^a and 124^b, are illustrated free, ready to be incorporated in several circuits as several radio frequency transformers.

By the aforesaid construction and arrangement for the plurality of sets of my adjustable coils, by independent rotation of the knobs 112^a, 112^c and 112^d, it is possible to balance the several transformers with respect to each other; and after the same are balanced, it is possible by rotation of the knob 121 to simultaneously vary the frequencies passed by the balanced transformers.

By these means it is possible in some circuits to dispense entirely with variable condensers for tuning purposes.

I claim:

1. Electrical apparatus including a plurality of spaced brackets, a coil adjacent each bracket, independent adjustable means associated with each bracket for selectively adjusting and maintaining the adjacent coil at varying distances from the bracket, a movable coil adjacent each of the first mentioned coils, and means for varying the distance between each of the first mentioned coils and its adjacent movable coil.

2. Electrical apparatus including a plurality of spaced brackets, a coil adjacent each bracket, independent adjustable means associated with each bracket for selectively adjusting and maintaining the adjacent coil at varying distances from the bracket, a movable coil adjacent each of the first mentioned coils, and screw means for varying the distance between each of the first mentioned coils and its adjacent movable coil.

3. Electrical apparatus including a plurality of spaced brackets, a coil adjacent each bracket, independent adjustable means associated with each bracket for selectively adjusting and maintaining the adjacent coil at varying distances from the bracket, a mov-

- able coil adjacent each of the first mentioned coils, and means for simultaneously varying the distances between the first mentioned coils and their adjacent movable coils.
5. 4. Electrical apparatus including a plurality of spaced brackets, a coil adjacent each bracket, independent adjustable means associated with each bracket for selectively adjusting and maintaining the adjacent coil at varying distances from the bracket, a movable coil adjacent each of the first mentioned coils, and screw means for simultaneously varying the distances between the first mentioned coils and their adjacent movable coils.
- 10 15. 5. Electrical apparatus including a plurality of spaced brackets, a coil adjacent each bracket, independent adjustable means associated with each bracket for selectively ad-
- justing and maintaining the adjacent coil at varying distances from the bracket, a movable coil adjacent each of the first mentioned coils, and means for simultaneously moving all of the movable coils.
6. Electrical apparatus including a plurality of spaced brackets, a coil adjacent each bracket, independent adjustable means associated with each bracket for selectively adjusting and maintaining the adjacent coil at varying distances from the bracket, a movable coil adjacent each of the first mentioned coils, and screw means for simultaneously moving all of the movable coils.

In testimony that I claim the above, I have hereunto subscribed my name.

NICHOLAS MEDVED.
